[57] **CLAIM**

The ornamental design for the measuring instrument, as shown and described.

DESCRIPTION

FIG. 1 is a perspective view of a measuring instrument showing the new design with a boundary between areas of contrasting color which is visible through a window on the face thereof;

FIG. 2 is a front elevational view thereof;

FIG. 3 is a back elevational view thereof;

FIG. 4 is an elevational view of one of the sides thereof;

FIG. 5 is an elevational view of the other of the sides thereof;

FIG. 6 is a top plan view thereof; and,

FIG. 7 is a bottom plan view thereof.

The broken line showings are for illustrative purposes only and forms no part of the claimed design.
